TIRE

Eric C. Bartlett, Erdington, Birmingham, England, assignor to Dunlop Tire & Rubber Corporation, Buffalo, N.Y., a corporation

Filed Aug. 11, 1969, Ser. No. 18,614

Claims priority, application Great Britain Feb. 20, 1969

Term of patent 14 years

Int. Cl. D12—14

U.S. Cl. D90—20

FIG. 1

FIG. 2

FIG. 3

FIG. 1 is a perspective view of the tire of my new design,

FIG. 2 is a fragmentary perspective view,

FIG. 3 is a fragmentary plan view.

It is to be understood that the tread pattern continues as shown throughout the circumference of the tire and the sidewall opposite to that shown in FIG. 1 is the same.

I claim:

The ornamental design for a tire, as shown and described.
